UNITED STATES PATENT OFFICE.

JOHN FRANKLIN BOWES, OF NORTH ADAMS, MASSACHUSETTS.

VENTILATOR.

No. 856,762.

Specification of Letters Patent.

Patented June 11, 1907.

Application filed February 20, 1907. Serial No. 358,353.

To all whom it may concern:

Be it known that I, JOHN FRANKLIN BOWES, a citizen of the United States, and a resident of North Adams, in the county of 5 Berkshire and State of Massachusetts, have invented a new and Improved Ventilator, of which the following is a full, clear, and exact description.

This invention has in view the provision of 10 a ventilator such as are ordinarily removably placed in window openings of buildings, cars, etc. and which will automatically operate to close and shut off a draft of air on blowing therethrough. I accomplish this by swingingly suspending two or more sheets of thin 15 material within the opening of the ventilator frame, said sheets being slightly spaced apart and having slots or other openings arranged out of alinement, whereby as the sheets are 20 blown together, the ventilator is automatically closed, and when separated, the ventilator is likewise opened.

Reference is to be had to the accompanying drawings forming a part of this specification, 25 in which similar characters of reference indicate corresponding parts in all the figures.

Figure 1 is an inside perspective view of a window showing my improved ventilator applied thereto; Fig. 2 is a cross section through 30 the window frame and ventilator, as shown in Fig. 1; Fig. 3 is a side elevation of the ventilator, partly broken away to more clearly show the interior construction thereof, and Fig. 4 is a section on the line 4—4 of Fig. 3.

The preferred embodiment of my invention 35 comprises a rectangular or similarly shaped frame 1, having hinged at the opposite ends thereof, blocks 2 adapting said frame to be readily inserted between the 40 jambs of a window opening. The opening of the frame 1 is covered on both the front and back with a thin fabric, wire screen or other like material 3, which is held in place by a molding 4, the latter providing an ornamental border. As shown in Figs. 2 and 4, 45 the coverings 3 form an air chamber on the inside of the frame 1 equal to the thickness thereof. Within this air chamber is swingingly suspended at its top edge a sheet or 50 wall of thin material 5, as for example, paper, said sheet being of an extent to fill the opening within the frame 1, and is constructed with a series of slots or other openings 6, as clearly shown in Fig. 1, the slots preferably 55 running in a vertical direction and dividing the sheet into vertical bars 7 connected together

by a lower horizontal bar 8. Slightly spaced from the sheet 5 is a sheet or wall 5^a of like thin material swingingly suspended from the top of the air chamber, as clearly 60 shown in Fig. 4. The sheet 5^a is also of an extent to substantially cover the frame opening, and is likewise constructed with a series of vertical slots or other openings 6^a dividing the sheet into a number 65 of vertical bars 7^a connected together at their lower ends by a horizontal bar 8^a. The bars 7^a of the sheet 5^a are arranged opposite the slots or openings 6 of the sheet 5; that is, they are arranged between the intervals of the 70 bars 7 of the sheet 5, and are somewhat wider and shorter than the slots or openings 6, as clearly shown in Fig. 3, whereby when said sheets swing together they will present a solid wall within the ventilator opening and thus 75 prevent the air from passing therethrough. It is apparent from this construction that when the wind blows through the outside covering and comes in contact with the bars of the outside sheet, the same will be caused 80 to move inwardly in contact with the inner sheet, thus automatically shutting off all wind or draft through the ventilator, which will last as long as the wind continues to hold the sheets in contact. The wind on easing up, 85 the sheets will automatically separate and thus open the ventilator. The latter will continue to close and open at all times without any attention whatsoever. It is apparent from this construction that a room or other 90 inclosure in which my improved ventilator is used, may be supplied with the requisite quantity of fresh air without subjecting those within, to any undue draft.

Although I have shown and described my 95 invention as it is preferably arranged and constructed, I nevertheless regard the precise embodiment as not essential provided the essential characteristics are employed as pointed out in the annexed claims.

Having thus described my invention I claim as new and desire to secure by Letters Patent:

1. A ventilator comprising a frame, a sheet of material swingingly suspended within the frame having openings, and a second sheet of material suspended within the frame and having openings out of alinement with the openings in the first sheet, whereby as said sheets are blown together, the ventilator will be 100 closed, and when they separate, the ventilator will be opened.

2. A ventilator comprising a frame, a sheet of thin material having openings swingingly suspended within the frame, and a second sheet of thin material and swingingly suspended within the frame having openings out of alinement with the openings of the first sheet, whereby as said sheets are blown together, the ventilator will be closed, and when they separate, the ventilator will be opened.
3. A ventilator comprising a frame having an opening, a covering at both sides of said opening providing an air chamber, a sheet of thin material having openings and swingingly suspended within the frame having openings out of alinement with the openings of the first sheet, whereby as said sheets are blown together, the ventilator will be closed, and when they separate, the ventilator will be opened.
4. A ventilator comprising a frame having an opening, blocks hinged at the opposite ends of the frame, a covering at both sides of the frame opening providing an air chamber therebetween, a sheet of thin material having

openings and swingingly suspended within the frame, and a second sheet of thin material swingingly suspended within the frame and having openings out of alinement with the openings in the first sheet, whereby as 30 said sheets are blown together the ventilator will be closed, and when they separate the ventilator will be opened.

5. A ventilator comprising a frame, a sheet of thin material having openings and swingingly suspended at its top edge within the frame, and a second sheet of thin material swingingly suspended at its top edge within the frame and having openings out of alinement with the openings in the first sheet, 40 whereby as said sheets are blown together, the ventilator will be closed, and when they separate, the ventilator will be opened.

In testimony whereof I have signed my name to this specification in the presence of 45 two subscribing witnesses.

JOHN FRANKLIN BOWES.
